UNITED STATES PATENT OFFICE.

THEODOR BERNHARD GEORG JANSSEN, OF MÜNSTER, GERMANY.

ELECTRIC-CURRENT COLLECTOR.

1,123,543.

Specification of Letters Patent.

Patented Jan. 5, 1915.

Application filed March 27, 1914. Serial No. 827,736.

To all whom it may concern:

Be it known that I, THEODOR BERNHARD GEORG JANSSEN, a subject of the Emperor of Germany, residing at 54 Gallitzinstrasse, 5 Münster, Westphalia, in the German Empire, have invented certain new and useful Improvements in Electric-Current Collectors, of which the following is a specification.

The invention relates to electric current 10 collectors for use in connection with the electric lighting of bicycle and motor car lamps of the kind in which the necessary current is generated during running.

The invention resides broadly in the fact 15 that the brush or collector is devised for automatic adjustment. With this object the conducting wire connected with the brush is resilient, and bears against a suitable support for the purpose of maintaining 20 the pressure upon the brush.

An embodiment of the invention is illustrated by way of example in the accompanying drawing, in which—

Figure 1 shows the device in vertical section, Fig. 2 is a rear elevation thereof, Fig. 25 Fig. 3 is a section on the line A—A of Figs. 1 and 2, Fig. 4 is a detail from Fig. 3 to a larger scale, Fig. 5 is a partial side elevation corresponding to Fig. 2.

The generator consists of the suitably 30 constructed magnet with the armature 1 rotating therein with slight clearance. The shaft 2 of this armature passes through a bore 4 in the yoke of the magnet 5, with the 35 interposition of a ball bearing and carries a friction disk 6 engaging against a circular rotating part of the vehicle. When the device is fitted to a bicycle, for example this 40 rotating part may advantageously consist of an india rubber ring whose diameter is adjustable by means of clamping plates somewhat after the manner adopted in connection with bottle stoppering devices.

The rotary movements transmitted during 45 running by the rotating part of the vehicle to the friction disk 6 and thereby to the shaft 2 is utilized in known manner, which forms no part of the present inven-

tion by means of the armature 1 for producing current for the supply of current to 50 electric lamps.

One end of the armature winding is in 55 electrical connection with the lamp holder 7, and the reflector adapted to be fitted thereto, and which in the known manner is electrically connected with one of the two poles of the incandescent bulb, while from the second pole of the bulb, which is insulated from the reflector, a wire cable 10 provided with an insulating covering 9 leads to 60 the brush 11. In the example illustrated the brush consists of a tubular metal casing or socket 11 open at its outer end, the conductor 10 resting against the reinforced or thick bottom of this casing which serves for 65 taking the current. The wire 10 is arranged so as to be resilient inside the casing 11, so that, in the example illustrated in Fig. 3, the brush 11 rests with its base yieldingly against the insulated ring 12. With this 70 object the wire 10 is spirally coiled in the casing 11 outside of which it bears against a suitable fixed part or shoulder 13.

The base of the casing which serves to 75 take the current is displaceable rectilinearly in an appropriate bore in a guide bush 15 of ebonite or the like adapted to be inserted in an opening in the wall or cover 14 of the apparatus. The guide bush 15 at the bottom of the bore for the casing 11 is provided with a shoulder 13 which constitutes a bearing for the spiral spring 10, constituted by the conductor, for automatically 80 adjusting the brush. In the insulated metal ring 12, against which the brush 11 is 85 pressed by the spring action of the wire 10, the second end of the armature winding 16 terminates, so that the circuit is thereby closed. In the case of continuous current machines a commutator is substituted for 90 the contact ring 12, and it is necessary to provide an even number of brushes. The bush 15 may be provided with an extension for the reception of the india rubber insulating tube 9 of the conductor 10. 95

As the armature 1 rotates on a step bear-

ing 17 below and in a ball bearing 3 above, the armature may assume a slight obliquity in manufacture, because the opening 4 for the shaft 2 must be bored in the magnet 5 before it is hardened, and it is found that it frequently becomes non-circular and distorted in the hardening operation. This obliquity of the axis of the armature, which cannot be easily remedied subsequently, 10 differs in every apparatus, according to the degree of distortion of the hole 4, even if the magnets are manufactured with the greatest care. As friction is reduced by the upper ball bearing 3, this obliquity of the armature presents no inconvenience, but nevertheless, according to the direction of the obliquity of the axis, the commutators or contact ring 12 on the armature shaft will act eccentrically with regard to the 15 brush. In practice it is therefore essential to provide for exact adjustment of the brush 11. To insure uniform running of the apparatus and to avoid loss of power resulting from unnecessary friction, the springs 10, 20 which are produced mechanically, must all be of the same strength and their tension must be exactly adapted to the interval between the contact or commutator rings 12 and the brushes and this result can be attained by forcing or screwing the bushes 15 into the wall of the casing to a greater or less depth. This adjustment is rendered possible because the insulating and guide bush 15 serves internally as a bearing for 25 the spring 10, while it is accessible from the exterior without difficulty, as it is inserted into the cover 14 from the exterior. For the purpose of replacing the brush 11 it is only necessary to remove the bush 15.

40 The arrangement described also presents other important advantages. When the bush 15 is removed it can be used directly for interposing a dry battery or an accumulator when the device is fitted for instance to a bicycle. In the case of a bicycle it is only necessary for this purpose to connect one pole of such a battery permanently with the casing of the apparatus and, in case of need, for example when the bicycle 45 is not running, to connect the bush 15 with the other pole of the source of current, in order to supply it from the latter. Owing to the fact that, as already stated the interval between the commutator or the collector 50 ring 12 and the brush varies it may happen that the reinforced base of the metal casing 11 which collects the current must protrude considerably from the bush 15 in order to make contact with the ring 12, whereby its 55 guidance in the bush is affected. Accordingly it is advantageous to guide the brush 11 in such a manner that even when it has to project considerably from its guide bush 15 in order to reach the ring 12, it is still

efficiently guided, so that it will not follow 65 the ring in its movement of rotation, and, moreover, the pressure exerted by the rotation of the ring 12 upon the bush 15 in the direction of rotation is distributed over so large a surface of the bush 15 that breakage 70 of the latter which would cause interruption of the current is avoided. If this result were attained by giving the brush 11 the form of a long solid cylinder, which would be the most obvious method to adopt, but 75 little space would be afforded in the bush for fitting a spiral spring of sufficient length to correspond with the considerable difference of length resulting from the varying amount of protrusion due to the obliquity 80 of the axis, or else it would be necessary to give the bush 15 a sufficient length for the reception of the spring 10. As, however, the length of the bush inside the casing is determined by the minimum interval 85 between the wall 14 and the collector ring 12, it would be necessary to arrange the greater length of the bush outside the casing, where, as the bush consists of brittle material, it would be particularly liable to fracture, 90 owing to its length. In order, therefore, to avoid having any considerable length of bush outside the casing while nevertheless obtaining the conditions of guidance set forth above, it has been found desirable to 95 adopt the following arrangement: The brush 11 is not constructed as a solid cylinder but as a hollow cylinder and only its lower thick solid end serves for collecting the current. The spring 10 extends into the 100 cylinder 11 so that a sufficient length is provided for its reception without lengthening the bush 15 in a manner dangerous in operation. The arrangement of the hollow cylinder, into which the spring serving to 105 adjust it extends, renders it possible to utilize the length required for guiding the casing 11 in the bush 15 for the arrangement of the spiral spring. If the reinforced current collecting end of the cylinder 11 is 110 pressed a long way out of the guide 15 in order to reach the ring 12, the cylinder 11 is nevertheless given a guidance of adequate length because the outer end of the hollow cylinder 11 normally extends almost to the 115 shoulder 13 of the bush 15, whereby the entire length thereof is fully utilized, which is only possible if a hollow cylinder 11 be employed, while even when the cylinder 11 is pressed farther inward a sufficient length 120 is guided within inner walls of the bush and the pressure exerted upon it in the direction of rotation is distributed over so large a surface of the bush that the pressure is insufficient to break it.

125 What I claim and desire to secure by Letters Patent is:—

A current collector for use in connection

with electric lighting of cycles and motor cars, comprising a bush socket of insulating material, a shoulder at the bottom of the bore of said socket, a tubular brush 5 closed at one end and longitudinally movable in said socket, a conductor passing through an opening in the outer end of said socket and in the form of a spiral coil within said socket the free end of the coil bearing against the bottom of the bore of the 10

tubular brush and the other end of the coil bearing against the bottom of the bore of the bush socket, substantially as set forth.

In testimony whereof I have affixed my signature in presence of two witnesses.

THEODOR BERNHARD GEORG JANSSEN.
